D. H. DOTTERER, OF PHILADELPHIA, PENNSYLVANIA.

Letters Patent No. 74,899, dated February 25, 1868.

APPARATUS FOR HEATING AND VENTILATING RAILWAY-CARS.

The Schedule referred to in these Letters Patent and making part of the same.

TO ALL WHOM IT MAY CONCERN:

Be it known that I, D. H. DOTTERER, of Philadelphia, Pennsylvania, have invented an Improved Method of Heating and Ventilating Railroad-Cars; and I do hereby declare the following to be a full, clear, and exact description of the same.

My invention relates to a method of supplying heated or cold air to a series of cars composing a railway-train; and it consists in the combining for this purpose, within a car placed at a suitable point in the train, of a fireplace, with certain apparatus, fully described hereafter, whereby a current of hot or cold air may be created and maintained through pipes or conduits, by which the said air is conducted to and distributed within the several cars. In the drawing, which forms a part of this specification—

Figure 1 is a side view, partly in section, showing my improved mode of heating and ventilating cars.

Figure 2, a transverse sectional view on the line 1-2, fig. 1.

Figure 3, a plan view, partly in section, of the car within which the heating and ventilating-apparatus is contained; and

Figure 4, an inverted plan, showing the arrangement of the pipes or conduits by which the air is conveyed and distributed within the several cars.

Similar letters refer to similar parts throughout the several views.

A is the car within which my heating and ventilating-apparatus is contained; B representing one of a train of cars which it may be desired to heat or ventilate. At a suitable point within the car A, I securely fix a casing, a, containing a fireplace, of which a' is the chimney, b the ash-pit, and b' the fire-door. Surrounding the casing a' at a slight distance therefrom, is another casing, c, the space between the two casings serving as a steam-boiler, for the purpose hereinafter set forth. The whole is enclosed within a drum, d, the space d', between which and the casing c, serves as an air-heating chamber. To a crank-shaft, e, outside the drum d, and within a suitable box, e', with open sides, is hung an ordinary fan-blower, f, a pipe, f', serving as a communication between the interior of the box e' and that of the drum d. Motion is communicated to the crank-shaft e by a connecting-rod, g, of a steam-cylinder, D, secured to a suitable bed-plate, and to which steam is supplied by the pipe h communicating with the steam-boiler c.

Beneath the car A are two pipes, j and j', communicating, by means of a branch, at their outer ends, as shown in the inverted plan view; and beneath the cars to be heated or ventilated are arranged pipes, k and k', similar to and in a line with the pipes j and j', with which they are connected by tubes, m m, of India rubber or other suitable flexible material. The pipe j of the car A communicates with the pipe f' by means of a vertical pipe, l, fig. 1, and also with the interior of the drum d through an opening, x. The pipe j' may also communicate with the drum d through a similar opening, x'.

A valve or damper, l', in the pipe l, serves to intercept the communication between the pipes f' and j; and by means of a similar valve, p, situated at a point in the pipe f' between the pipe l and the drum d, the communication between the latter and the pipe f' may be closed.

When it is desired to supply heated air to the cars of a train, the valve l' is closed, and the valve p being opened, the fan-blower f is caused to revolve rapidly in the direction of the arrow, and draws through the open sides of the box in which it is contained a stream of air, which it propels forcibly through the pipe j' into the air-chamber d'. The air, after traversing this chamber, and becoming thoroughly heated by contact with the casing c of the boiler, enters the pipe j through the opening x. From the pipes j and j' the current of heated air is conveyed, through the flexible connecting-tubes m, to the pipes k and k' of the cars to be heated, to which it is admitted, at suitable intervals, through openings in the pipes k and k', and corresponding openings in the floor of the car, as illustrated at y, fig. 1, the quantity of air admitted through these openings being regulated by means of ordinary registers.

It will be easily seen that in this manner all the cars of a railway-train may be effectually, pleasantly, and economically warmed, the disagreeable inequality and repeated changes of temperature, so detrimental to health, and the liability to accident attending ordinary methods of heating, being entirely obviated.

It will also be seen that my apparatus may be used with advantage for supplying cool air to the cars in summer. When it is desired to do this, it is merely necessary to close the valve p and open the valve l', so that

the air propelled by the fan-blower, instead of passing through the air-heating chamber, and thence to the pipes *j* and *j'*, passes directly to the latter from the pipe *f*', through the connecting-pipe *l*, and will be conveyed to the pipes *k* and *k'*, and thence admitted to the cars.

In this manner a constant stream of pure, cool air, may be maintained within the cars, unattended by the disagreeable stream of dust which accompanies the air when admitted through the open windows.

If desired, a number of pipes may be secured to the casing *d*, within the air-heating chamber *d'*, and communicating with the interior of the steam-boiler *c*, so that currents of steam or hot water may pass through the said pipes for the purpose of more thoroughly heating the air contained in the chamber *d'*.

Without, therefore, confining myself to the precise arrangement of parts herein described.

What I claim as my invention, and desire to secure by Letters Patent, is—

The within-described combination of furnace, boiler, air-heating chamber, and engine, with the fan-blower, or equivalent device, whereby a forcible-current of heated or cold air is created and maintained through pipes, which convey the air to and distribute it within the several cars of a railroad-train, substantially in the manner described.

In testimony whereof, I have signed my name to this specification in the presence of two subscribing witnesses.

D. H. DOTTERER.
